UNITED STATES PATENT OFFICE.

JOHN F. TEEHAN, OF BROCKTON, MASSACHUSETTS.

FOOTWEAR.

1,420,461.

Specification of Letters Patent. Patented June 20, 1922.

Application filed November 10, 1921. Serial No. 514,142.

To all whom it may concern:

Be it known that I, JOHN F. TEEHAN, a citizen of the United States, residing at Brockton, in the county of Plymouth and 5 State of Massachusetts, have invented new and useful Improvements in Footwear, of which the following is a specification.

This invention has relation to the manufacture of footwear and more particularly 10 to welt shoes, having for its object to produce a shoe which is highly flexible and which affords the greatest comfort to the wearer.

In accordance with the present invention, 15 the innersole of the shoe is so constructed as to form two layers or members at the shank and at the forepart with a substantially continuous rib extending from the heel along the shank around the forepart 20 and back to the heel for the attachment of the upper and the welt. This may best be accomplished by splitting the innersole from the heel to the front end of the shank and from the toe so as to leave an unslit portion 25 extending transversely of the innersole approximately at the ball thereof.

On the accompanying drawings,—

Figure 1 represents in plan view an innersole embodying the invention.

30 Figure 2 represents a longitudinal section through the same on the line 2—2 of Figure 1.

Figure 3 represents the bottom of the shoe having the innersole, the welt and upper all attached.

Figure 4 represents an enlarged section on the line 4—4 of Figure 3.

Figure 5 represents a somewhat similar section on the line 5—5 of Figure 3.

40 Figure 6 shows a completed shoe and illustrates the manner in which the shank members of the innersole separate when the wearer is in the act of walking.

Figures 7 and 8 illustrate cross sections 45 through innersoles embodying the invention.

In preparing the innersole, it is necessary that it should be provided with a rib extending along the sides of the shank and around the forepart for the attachment of the upper 50 and the welt. This rib may be made in any of the usual ways in which such ribs are formed, as, for instance, by the employment of the usual channelling machines. Preferably the channelling operation is accomplished 55 after the innersole has been cut out

of a sheet of leather or other suitable material.

As shown in Figure 1, the innersole, which is indicated as a whole at *a*, is channeled to provide the rib *b* which extends 60 from heel to heel around the shank and the forepart, and also to provide the usual channel *c* and the channel flap *d*. The face of the innersole may be reinforced in any one of the usual ways. For example, it may 65 be channeled only along one edge, as shown in Figure 7, to provide the upstanding rib *b*; and, on the feather and against the outer face of the rib, there may be secured the reinforcing strip *e* formed of fabric and 70 coated with the usual compound which is employed in making Gem cloth so-called. If desired, however, the entire face of the insole, including the rib and the feather, may be covered with a reinforcing canvas 75 layer *f* of cloth cemented in place.

The innersole is preferably split inwardly from the heel end and from the toe end, as shown in Figure 2, leaving a portion of the material uncut as indicated at *g*. This uncut 80 or solid portion extends transversely of the innersole and is located substantially at the ball, so that there are provided the two toe or front members *h* and *i* and the two shank or rear members *j* and *k*. It will be observed 85 that the rib of the innersole is continuous and is formed on the members *h* and *j* and on the intermediate portion of the innersole. The other members *i* and *k* are free at their extremities so that, when the innersole is 90 bent, both members may slide on the members *h* and *j*. Preferably the plane of separation of the upper and lower members is between the face of the feather and the opposite face of the innersole, as shown in the 95 various figures of the drawing.

When the shoe is finished, the welt 10 is stitched to the innersole, the stitches 11 (in Figure 5) passing through the between-substance at the base of the rib *b* and of the 100 channel flap *d*, when an innersole such as shown in Figure 1 is employed. Thus the continuous welt is secured to the two lower flap-like members *h* and *j* of the innersole, leaving the upper members *i* and *k* free to 105 move or bend relatively thereto. In this way, the flexibility of the shoe is greatly increased. Usually the extremity of the member *k* is secured to the member *j*, at a point over the heel, by fastenings *m* (see Figure 110

6) or by the nails which fasten the heel to the sole *n*. In some cases, I may secure to the inner face of one or the other of the members *j, k* a reinforcing fabric *o* treated with some damp-proof material or with some substance for reducing friction.

Various changes may be made in the embodiment of the invention thus illustrated and described without departing from the 10 spirit and scope of the invention as defined in the claims.

Having thus explained the nature of my said invention and described a way of making and using the same, although without attempting to set forth all of the forms in 15 which it may be made or all of the modes of its use, what I claim is:—

1. An innersole for welt shoes having a rib extending from heel to heel around the 20 forepart, said innersole comprising an upper member and a lower member which are attached together at substantially the ball portion and are loose at the toe end and shank.

2. An innersole for welt shoes having a 25 welt-attaching rib extending around the forepart and shank, said innersole being split at the heel and toe to provide two members integrally connected approximately at the ball of the innersole.

3. A welt shoe comprising a welt, an upper, and an innersole having a continuous rib extending around the shank and forepart thereof and stitched to the welt and upper, said innersole comprising an upper and a 35 lower member connected at approximately the ball of the shoe but free therefrom at the toe and the shank.

4. A welt shoe comprising a welt, an upper, and an innersole having a continuous 40 rib extending around the shank and forepart thereof and stitched to the welt and upper, said innersole being split at the shank and at the toe end and integrally connected approximately at the ball of the shoe.

In testimony whereof I have affixed my 45 signature.

JOHN F. TEEHAN.
